Primary Examiner—Philip S. Hyder

[57] CLAIM

The ornamental design for a circular saw blade case, as shown.

DESCRIPTION

FIG. 1 is a front view of the circular saw blade case of the present invention;

FIG. 2 is a rear view of the circular saw blade case of FIG. 1;

FIG. 3 is a left side view of the circular saw blade case of FIG. 1;

FIG. 4 is a right side view of the circular saw blade case of FIG. 1;

FIG. 5 is a top view of the circular saw blade case of FIG. 1;

FIG. 6 is a bottom view of the circular saw blade case of FIG. 1; and,

FIG. 7 is a perspective view of the circular saw blade case of FIG. 1, wherein the cover is shown in an open position. The broken line showing of the saw blade in FIG. 7 is for illustrative purposes only and forms no part of the claimed design.
